THREAD PARTING MECHANISM

George F. Belforti, Milford, Mass., assignor to
 Draper Corporation, Hopedale, Mass., a corporation of Maine

Application March 3, 1941, Serial No. 381,527

13 Claims. (Cl. 139—263)

This invention pertains to automatic filling replenishing looms and has more particular reference to thread parting mechanism for parting the incoming filling ends formed by such looms.

The usual automatic filling replenishing loom includes a reciprocating lay having a shuttle box at the replenishing end thereof, filling replenishing mechanism including a magazine containing a plurality of reserve filling carriers and providing means for holding the filling ends of the reserve carriers, mechanism for severing the filling ends adjacent the cloth selvage such as a temple thread cutter, and mechanism for clamping and parting the outgoing filling end adjacent the shuttle. In addition such looms may be provided with a thread remover, either mechanical or pneumatic for removing loose pieces of filling ends from the loom.

Operation of the replenishing mechanism incidentally results in the formation of an incoming filling end extending from the cloth selvage to the filling end holder and an out-going filling end extending from the cloth selvage to the parting and clamping mechanism, which mechanism operates at the time of transfer to clamp and sever the outgoing filling end from the exhausted filling carrier.

Upon severance of the outgoing and incoming filling ends adjacent the cloth selvage by the temple thread cutter the outgoing filling end is completely removed from the loom by the thread remover if one is provided. The incoming filling end after being severed at the cloth selvage is still attached to the filling end holder and may be caught in the moving parts of the loom, or if a thread remover is provided cannot be completely removed from the loom by the thread remover until it is parted from the filling end holder.

Since it is essential for the proper operation of the loom that the incoming filling end remain attached to the filling end holder for a plurality of picks after the operation of the replenishing mechanism, any parting of the incoming filling end from the holder must be delayed for a plurality of picks after the formation thereof.

A prior construction for parting the incoming filling ends adjacent the holder a plurality of picks after the formation thereof included a stationary parting mechanism positioned adjacent the holding means so that upon rotation of the magazine the incoming filling end would be moved into the parting mechanism and parted. Such device has proved unsatisfactory due to the

lack of a positive parting action. Another construction had parting means positioned adjacent the holder and having a movable blade operated by the peripheral surface of the thread guide disc acting as cam actuating means to operate the parting means. Such construction, however, has been too complicated, and difficult to adjust.

Accordingly it is a principal object of this invention to provide an automatic filling replenishing loom including replenishing mechanism comprising a magazine containing a plurality of reserve filling carriers, and having a filling end holder to which the filling ends of the reserve carriers are attached, a temple thread cutter, a filling end parting and clamping mechanism, parting mechanism for parting the incoming filling thread adjacent the filling end holder, and a new and improved operating means therefor which shall comprise a reciprocating means for actuating the parting mechanism said reciprocating means and said parting mechanism being so constructed and arranged as to effect parting of each newly formed incoming filling end a plurality of picks after the operation of the replenishing mechanism forming the same.

This and other objects of the invention are accomplished by the construction illustrated on the accompanying drawings, wherein;

Fig. 1 is a perspective view of the replenishing side of an automatic loom having the preferred embodiment of my invention applied thereto;

Fig. 2 is a plan view of certain mechanism shown on Fig. 1;

Fig. 3 is a side view of the incoming filling parter shown on Fig. 2 with the parting blades open; and

Fig. 4 is a view similar to that of Fig. 3 but with the parting blades closed.

The drawings show but parts of a loom, the parts and mechanisms not shown being of usual construction and forming no part of the present invention.

The parts shown include a reciprocating lay beam 1 having a reed 2 and a shuttle box 3 mounted thereon, a right hand side frame 4 and a breast beam 5 on which is mounted the replenishing mechanism.

The replenishing mechanism may be of any usual type, the particular construction shown being of the rotary battery type. Only a portion of the replenishing mechanism is shown, the portion shown including the transerrer 6 mounted on transerrer stub shaft 7, magazine 8 holding a plurality of reserve filling carriers or bobbins 9, thread guide disc 10, filling end holder 11 to

which are attached the ends of the filling on the bobbins 9 and means for rotating the magazine to successively present each reserve bobbin in transfer position, including ratchet 12 and feed pawl 13.

In addition to the foregoing the loom is shown as equipped with a temple thread cutter or selvage trimming mechanism for parting the incoming and outgoing filling ends adjacent the cloth selvage, a parting and clamping mechanism for parting and clamping the outgoing filling end adjacent the shuttle and a thread remover for removing loose pieces of filling ends formed by the parting mechanisms.

The temple thread cutter or selvage trimming mechanism may be of the usual construction and may comprise a lay operated cutter 14 mounted on the temple 15.

The thread remover may be similar to the thread remover described and claimed in the co-pending application of Carl D. Brown, Edward C. Nichols and George F. Belforti, Serial No. 331,844, filed April 26, 1940, now Patent No. 2,233,373, and may comprise a bracket 16 fixed to stub shaft 7 and carrying a conduit 17, and a reciprocating rod 18 pivotally attached to the lay beam for feeding the loose filling ends into and through the conduit.

The parting and clamping mechanism for parting the outgoing filling end may be similar to that described and claimed in the patent to Northrop No. 2,028,560, granted January 21, 1936, and may comprise parting and clamping blades 19 mounted on a carrier 20 which reciprocates in a guiding member 21 mounted on a bracket 22 attached to the stub shaft 7. Means are provided for opening and closing the parting and clamping blades including a blade operating member 23 and a pivoted cam 24, and means are provided for moving the carrier and the parting and clamping blades toward and from the shuttle box, including a swinging bracket 25 and a pin 26 projecting from the carrier 20, all as more fully described in the above referred to patent to Northrop.

The particular bracket shown for supporting the parting and clamping mechanism may be similar to that described and claimed in the patent to Nichols No. 2,223,896, granted October 25, 1940, and may comprise an upper member 27 adjustably attached to the stub shaft 7, a lower member 28, to which the carrier guide member 21 is attached, adjustably connected to the upper member 27 by means of a pivoted connection 29 at its forward end and a bolt and slot connection 30 at its rear end.

A shuttle 31 is shown in the shuttle box 3. Shuttle 31 carrying the filling supply is picked from side to side along the lay beam 1 by suitable means which may include a picker stick 32. As the shuttle is thus picked it lays filling thread in the shed S, which filling thread is beaten into the fell of the cloth C by the reed 2. When the filling supply in the shuttle is substantially exhausted, a fresh supply is provided by the automatic replenishing mechanism.

The transfer of a bobbin 9 to the shuttle 31 and the subsequent picking of the shuttle results in the formation of a length of filling thread which extends from the holder 11 through the shed S. The subsequent beating in of the portion of this thread which is in the shed leaves the end f projecting from the cloth selvage. This filling end is known in the art as the incoming filling end.

The operation of the replenishing mechanism

results in the formation of another filling end f' projecting from the cloth selvage. This filling end f' extends from the cloth selvage to the outgoing or exhausted bobbin in the shuttle and is known as the outgoing filling end. Thus the incoming and outgoing filling ends are formed incidental to the operation of the replenishing mechanism.

The outgoing filling end f' is parted adjacent the shuttle eye at the time of transfer by the parting and clamping blades 19. These blades part and clamp the outgoing filling end and withdraw it from the shuttle box.

The outgoing filling end f' and the incoming filling end f are severed adjacent the cloth selvage by the temple thread cutter 14 a few picks after transfer. The reciprocating rod 18 of the thread remover catches the outgoing and incoming filling ends after they have been severed by the temple thread cutter and feeds them into and along the conduit 17. Means are provided in the conduit for preventing retrograde movements of the filling ends as the rod 18 moves. Upon release of the outgoing filling end by the parting and clamping mechanism the loose piece of outgoing filling is completely fed through the conduit 17 and removed from the loom. The incoming filling end, however, has one end attached to the end holder 11 and cannot be completely fed through the conduit 17 and removed from the loom until it has been broken or severed from the end holder 11.

I provide a thread cutting mechanism for severing the incoming filling end f adjacent the thread holder. Such mechanism may comprise a rod 33 adjustably mounted on the rear end of the lower member 28 of the bracket supporting the parting and clamping mechanism. A depending bracket 34 is adjustably mounted on the outer end of rod 33 by means of set screw 35. Fixedly mounted on bracket 34 by means of bolt 36 is a thread guide member 37. The forward end of member 37 is slotted to receive a pin 38 projecting from the bracket 34. The rear end of member 37 is provided with an open ended slot 39 for the reception of the incoming filling end. The open end of slot 39 is V-shaped as at 40, and best seen in Figs. 3 and 4, the inner end of slot 39 forms a circular opening 41. A hook 42 is formed on member 37 and projects into the slot 39 adjacent the V-shaped opening.

A stationary blade 43 is fixedly mounted on bracket 34 by the bolt 36. The stationary blade has a slot at its forward end engaging the pin 38. A movable blade 44 is pivotally mounted on bolt 36 and has an opening 45 adjacent its forward end for the reception of pin 38. A pin 46 projects laterally from the front end of movable blade 44 for a purpose later to be described. The movable blade 44 is held in close contact with stationary blade 43 by means of a spring 47 and a member 48 mounted on bolt 36. The forward end of member 48 is slotted to receive pin 38.

A rod 49 is adjustably attached by means of set screw 50 to an upstanding lug 51 on the carrier 20. The rod 49 extends through an elongated slot 52 in the bracket member 28. A cam member 53 is adjustably attached to the outer end of rod 49 by means of set screw 54. Cam member 53 is provided with an elongated slot 55, which is inclined at an angle to the horizontal, for the reception of the pin 46 which projects from the movable blade 44. The walls of the slot 55 act as a cam surface and the pin 46 is the cam follower. When the carrier 20 moves rearwardly

toward the shuttle box the cam member 53 moves rearwardly and the pin 46 rides up the inclined slot 55 thereby moving the movable blade 44 to close the thread parter and part the filling thread, as the cam member 53 moves forwardly away from the shuttle box, the pin 46 rides down the inclined walls of slot 55 thereby opening the thread parter. Thus it is seen that each time the parting and clamping mechanism moves toward the shuttle box to part and clamp the outgoing filling end, the thread parter for parting the incoming filling end will operate.

Since it is essential that the incoming filling end remain attached to the holder 11 for at least three or four picks after transfer it is necessary that the parting mechanism for parting the incoming filling end be so arranged as to part the incoming filling several picks after transfer. This result is accomplished by the mechanism of my invention, for as each reserve bobbin in the magazine is moved into position for transfer, the filling end extending from the bobbin to the holder is brought into the slot 39 in the guide member 37, the hook 42 prevents the filling end from escaping from the slot. Upon transfer the filling end is moved further into the slot coming to rest in the circular opening 41 where it is in position to be severed upon the next operation of the transfer mechanism. Thus it is seen that each newly formed incoming filling is parted by the thread parting mechanism on the next succeeding operation of the replenishing mechanism from that which formed it.

Having thus fully described the preferred embodiment of my invention, I claim:

1. In a filling end parting mechanism for automatic filling replenishing looms of the type incidentally forming incoming and outgoing filling ends, the combination of a support, parting blades mounted thereon in position to engage an incoming filling end, an intermittently reciprocatory element, a cam follower mounted on one of said blades and a cam secured to the intermittently reciprocatory element and constantly engaging said cam follower for intermittently actuating said blades, said cam and said cam follower being constructed and arranged to actuate said blades to part each successive incoming filling end a plurality of picks after formation thereof.

2. In an automatic filling replenishing loom of the type incidentally forming incoming and outgoing filling ends, the combination of means for parting said filling ends at the cloth selvage, means for parting the outgoing filling end at the shuttle and means actuated by said second named means for parting each incoming filling end at the replenishing mechanism, said last named means being constructed and arranged to part each said incoming filling end a plurality of picks after formation thereof.

3. In an automatic filling replenishing loom of the type incidentally forming incoming and outgoing filling ends and including means for parting said filling ends at the cloth selvage, the combination of means for parting each outgoing filling end at the shuttle and means actuated by said second named means for parting the incoming filling end at the replenishing mechanism, said last named means being constructed and arranged to part each said incoming filling end a plurality of picks after formation thereof.

4. In an automatic filling replenishing loom of the type incidentally forming incoming and outgoing filling ends, the combination of means for

parting said filling ends at the cloth selvage, means for parting the outgoing filling end at the shuttle, means actuated by said second named means for parting the incoming filling end at the

5. replenishing mechanism, said last named means being constructed and arranged to part each said incoming filling end a plurality of picks after formation thereof and means for removing from the loom loose pieces of filling ends formed by said 10 parting means.

5. In a filling end parting mechanism for automatic filling replenishing looms of the type incidentally forming incoming and outgoing filling ends, the combination of a support, parting blades

15 mounted thereon, a guide member having an elongated slot therein with a circular opening at the closed end of said slot for holding said incoming filling ends in position to be parted by said blades, and an intermittently reciprocatory cam

20 member constantly engaging a projection extending from one of said blades for intermittently actuating the same, said member and said blades being constructed and arranged to effect parting of each successive incoming filling end a plurality of picks after formation thereof.

6. In a filling end parting mechanism for filling replenishing looms, a support, a pair of parting blades mounted thereon, one of said blades being fixedly mounted on said support, the other

30 of said blades being movable from an open to a closed position with a shearing action, a cam follower mounted on said movable blade, a cam member secured to an intermittently reciprocatory element of the loom and constantly engaging said cam follower, whereby said cam member on its rearward movement will move said movable blade to closed position and on its forward movement will move said movable blade to open position.

40 7. In a filling end parting mechanism for filling replenishing looms, a support mounted on said loom, a carrier slidably mounted on said support for intermittent movement forwardly and rearwardly of the loom, a cam mounted on said carrier

45 for movement therewith, means for moving said carrier, a pair of parting blades mounted on said support, one of said blades being fixed, the other of said blades being movable from open to closed position, a cam follower mounted on said movable blade and constantly engaging said cam to thereby move said movable blade to closed position on the rearward movement of said cam and move said movable blade to open position on the forward movement of said cam.

55 8. In a filling replenishing loom having a magazine for reserve filling carriers and means for transferring successive reserve filling carriers from the magazine to a shuttle, said loom being of the type incidentally forming incoming and outgoing filling ends, means for parting the outgoing filling end at the shuttle and a second parting means located outwardly of and actuated by

60 said first parting means for parting the incoming filling end close to the magazine.

65 9. In a filling replenishing loom having a magazine for reserve filling carriers and means for transferring successive filling carriers from the magazine to a shuttle, said loom being of the type incidentally forming incoming and outgoing filling ends, means for parting the outgoing filling end at the shuttle and a second parting means located outwardly of and actuated by

70 said first parting means for parting the incoming filling end at the magazine a plurality of picks after the formation thereof.

10. In a filling replenishing loom having a magazine for reserve filling carriers, a means spaced apart from the magazine for holding filling ends extending from said reserve filling carriers, means for transferring successive reserve filling carriers from said magazine to a shuttle and for displacing a used filling carrier from the shuttle, means for parting at the shuttle the filling end extending from the used filling carrier, and parting means actuated by said first parting means for parting at said holding means filling ends extending from said reserve filling carriers.

11. In a filling replenishing loom having a magazine for reserve filling carriers, a holding means spaced apart from said magazine for holding filling ends extending from said reserve filling carrier, means for transferring successive reserve filling carriers to a shuttle and to displace a used filling carrier from the shuttle, means for parting at the shuttle a filling end extending from the selvage to the used filling carrier, and means actuated by said parting means for parting successively the filling ends secured to the said holding means at a point between the magazine and the holding means.

12. In a filling replenishing loom having a magazine for reserve filling carriers, a holding means spaced apart from said magazine for securing the ends of filling extending from said reserve filling carriers, a support placed on the loom between said magazine and said holding means, a

parting means mounted on said support, said parting means having a movable blade with a cam follower mounted thereon, a reciprocatory cam engaging said cam follower to actuate said movable blade, means for guiding a filling end extending from said magazine to said holding means and for placing it in engagement with said parting means whereby, upon actuation of said parting means, said filling end is parted at a point between said magazine and said holding means.

13. In a filling replenishing loom having a magazine for reserve filling carriers and a holding means for securing the ends of filling extending from said reserve carriers, means for transferring successive reserve carriers from said magazine to a shuttle and to displace a used filling carrier from the shuttle, a parting means reciprocably engaging a filling end extending from the used filling carrier to the selvage to part the same, a cam moving with said parting means, a second parting means mounted on the loom proximate to said first parting means and at a point adjacent said holding means, a cam follower extending from a movable blade on said second parting means and engaging said cam on said first parting means whereby, upon actuation of said first parting means said second parting means is operated to part a filling end secured to said holding means.

GEORGE F. BELFORTI.
